UNITED STATES PATENT OFFICE

91,312

DESIGN FOR AN OIL BURNING HEATER

William T. Bradbury, Kankakee, Ill., assignor to Florence Stove Company, Gardner, Mass., a corporation of Massachusetts

Application November 1, 1933. Serial No. 49,624

Term of patent 7 years

To all whom it may concern:

Be it known that I, WILLIAM T. BRADBURY, a citizen of the United States, residing at Kankakee, in the county of Kankakee and State of Illinois, have invented a new, original, and ornamental Design for an Oil Burning Heater, of which the following is a specification, reference being had to the accompanying drawing, forming part thereof.

The figure is a perspective view of an oil burning heater showing my new design.

I claim:

The ornamental design for an oil burning heater substantially as shown.

WILLIAM T. BRADBURY.
